UNITED STATES PATENT OFFICE.

WILLIAM F. ALBRECHT AND SANDFIELD A. GHENT, OF CHICAGO, ILLINOIS.

MEMORIAL ALBUM.

No. 839,251.

Specification of Letters Patent.

Patented Dec. 25, 1906.

Application filed February 26, 1906. Serial No. 303,080.

To all whom it may concern:

Be it known that we, WILLIAM F. ALBRECHT and SANDFIELD A. GHENT, citizens of the United States, residing at Chicago, in the county of Cook and State of Illinois, have invented a new and useful Memorial Album, of which the following is a specification.

This invention relates to memorial albums, and has for its object to provide a comparatively simple and inexpensive device of the class described especially designed for use as an advertising medium by undertakers, funeral directors, and similar persons, and adapted to be used as a memorial for preserving various data descriptive of deceased persons.

A further object of the invention is to provide an album having its cover formed with a pocket for the reception of a photograph and its leaves ruled and printed in such a manner as to facilitate the recordation of any particular fact or facts relative to the person whose photograph is contained within the pocket.

With these and other objects in view the invention consists in the construction and novel combination and arrangement of parts hereinafter fully described, and illustrated in the accompanying drawings, it being understood that various changes in form, proportions, and minor details of construction may be resorted to within the scope of the appended claim.

In the accompanying drawings, forming a part of this specification, Figure 1 is a front elevation of the album, showing the same open. Fig. 2 is a similar view displaying the intermediate leaves. Fig. 3 is a front elevation of the rear leaf of the book. Fig. 4 is a front elevation of the album closed.

Similar numerals of reference indicate corresponding parts in all of the figures of the drawings.

The improved device is principally designed as a memorial for preserving an accurate record of various data relative to deceased persons and in its preferred embodiment consists of a cover 5, to which are sewed or otherwise secured a plurality of leaves 6.

The corners of the cover at one end thereof are provided with diagonal slits 7, forming marginal flaps 8, the ends of which are cut on curved lines, as indicated at 9, and folded downwardly upon the adjacent portion of the cover to produce a pocket having an elliptical-shaped opening 10 formed therein for displaying a photograph 12. The mouth 13 of the pocket is preferably disposed parallel with the adjacent longitudinal edges of the leaves 6, so as to facilitate the introduction and removal of the photograph 12 and also to prevent accidental displacement of said photograph.

The several leaves are preferably ruled, as shown, and stamped or otherwise printed on the front leaf of the album is descriptive matter to facilitate the recordation of the name of the deceased person, his birthplace, the place and date of his death, and the age of said person. On the opposite side of the front page may be recorded the name of the church in which the services were conducted, the place of interment, and the names of the several masonic or social orders that took part in the funeral ceremonies. The adjacent leaf of the album is designed to receive the names of the several pall-bearers who officiated at the obsequies, and printed on the lower portion of said leaf may be the name of the undertaker by whom the memorial album is presented. Upon the opposite side of the leaf are a plurality of spaced lines upon which may be written the names of persons tendering floral offerings, together with a short description of the nature of the floral pieces.

It will thus be seen that the album forms a convenient means for recording various facts relative to a deceased person, and being extremely simple in construction may be manufactured at a small cost and presented as an advertising medium to the relatives of the deceased.

Having thus described the invention, what is claimed is—

A memorial album consisting of a cover having its corners at one end thereof provided with diagonal slits forming marginal flaps the ends of which are cut on a curved line and adapted to be folded downwardly on the adjacent portion of the cover to produce a pocket having a display-opening formed therein for the reception of a photograph, and a plurality of leaves secured to the cover and adapted to receive descriptive matter relating to the photograph.

5 In testimony that we claim the foregoing as our own we have hereto affixed our signatures in the presence of two witnesses.
